Design No. 3,707, dated October 5, 1869.

DESIGN FOR A TRADE-MARK.

The Schedule referred to in these Letters Patent and making part of the same.

To all whom it may concern:

Be it known that I, GEORGE C. THILENIUS, of the city of Cape Girardeau, in the county of Cape Girardeau, and State of Missouri, have originated and designed a new Design for a Trade-Mark, of which the following is a full, clear, and exact description, reference being had to the accompanying drawings, making part of this specification.

The words "Cape City Mills, Cape Girardeau, Mo.," are in a circle of fourteen inches in diameter, the letters composing "Cape City Mills" being one and five-eighths of an inch, and the letters composing the words "Cape Girardeau, Mo.," being thirteen-sixteenths of an inch.

In the centre of this circle is the following inscription, "Choice 196 XXX Family Flour," underneath which are two arrow-heads reversed, pointing to the right and left, with ball between them, underneath which is the name "G. C. Thilenius."

What I claim as my invention, and desire to secure by Letters Patent, is—

The design for a trade-mark, herein set forth.
G. C. THILENIUS.
